UNITED STATES PATENT OFFICE.

MINARD A. POSSONS, OF CLEVELAND, OHIO, ASSIGNOR TO AMERICAN STOVE COMPANY, OF ST. LOUIS, MISSOURI, A CORPORATION OF NEW JERSEY.

RANGE SPLASHBOARD, TOP SHELF, AND BRACKET THEREFOR.

Application filed April 12, 1926. Serial No. 101,566.

This invention relates to improvements in range splash boards, top shelves and brackets therefor, as will be fully described herein-after.

5 The primary object of the present invention is to so provide a supporting bracket for the splash board and top shelf of a range that when it is so applied it is substantially invisible from the front of the stove.

10 A further object of the invention is to provide an efficient support for the splash board and the top shelf that leaves the open burner part of the range entirely free of any projecting extension whatever, and making 15 a sanitary construction.

A further object of the invention is to so construct the top shelf and the splash board as to receive the supporting bracket in such a manner as to make it substantially out of 20 sight from the front of the range.

Another object of the invention is to so construct the supporting bracket that its vertical part is adapted to be applied to the splash board and its horizontal portion to 25 the top shelf, and at the same time in a manner that will make the bracket substantially invisible from the front of the range.

Further objects of the invention will appear from the following description.

30 In the drawings:—

Figure 1 is a perspective view of that portion of the range which carries my present improvements.

Figure 2 is a detached perspective view 35 of the supporting bracket.

Figure 3 is a detached view of a supplementary support or bracket for the lower end of the supporting bracket.

Figure 4 is an inverted perspective view 40 of the top shelf.

Figure 5 is a detached inside perspective view of the triangular bracket.

Figure 6 is a horizontal cross sectional view of the splash board with the supporting bracket applied thereto.

Figure 7 is a vertical sectional view taken through the splash board and top shelf looking in the direction indicated by the arrow.

In carrying out the present invention certain well known parts of the structure of a range are utilized. For instance the oven portion 1 may be used in the usual form, and that is also true of the wall 2 which is next to the open burner frame 3. This open

burner frame may be the same shape in cross section, it having at its rear edge a downwardly projecting flange 4.

The splash board 5, however, in detail, is somewhat differently constructed from the ordinary splash board, as will be presently 60 described.

The brace rod 6 is located at the rear side of the splash board 5 and is L-shaped in general contour and is also L-shaped in cross section. The leg 7 of the brace bar 6 extends 65 from its upper end to near its lower end and is cut away as shown at 8, leaving its lower right angle end 9 projecting rearwardly from the other leg 10 of the brace bar. For the purpose of strengthening this brace bar 70 6 is provided a thickening ridge 11 located at the junction of the vertical portion with the horizontal portion of the brace bar. The horizontal portion of this brace bar extends under the top shelf 12, and located under 75 the horizontal portion 10' is substantially a triangular bracket 13. This bracket 13 has around its edges an inwardly extending flange that extends entirely around it. The top flange 14 engages the under side of the 80 leg 10 of this brace bar and the vertical flange 15 rests against the splash board 5 which in turn is in contact with the vertical leg 10 of the brace bar 6. The curved portion of this triangular bracket is provided 85 with a flange 16.

As here shown the top shelf 12 has its outer edge 17 turned downward preferably a little below the lower leg 10' of the brace bar and the lower edge of this flange is 90 doubled backward and upward as shown at 18. The end of this shelf 12 is also doubled downward outside of the leg 7' of the brace bar as at 19 and the lower edge of this turned down portion 19 is bent inward as shown at 95 20 and is in engagement with the under side of the leg 10' of the brace bar and with the upper side of the flange 14 of the triangular bracket 13. These three parts, that is the leg 10' and the flanges 20 and 14 are secured 100 together by means of suitable clamping bolts 21. These clamping bolts preferably have only their heads that show under the flange 14. Similarly the splash board 5 rests against the vertical leg 10 of the brace bar 105 and is located between it and the vertical flange of the triangular portion 13. These three parts are secured together by a suitable

bolt 23, which preferably has only the head of the bolt exposed to the front of the splash board. This top shelf also has its inner edge bent downward into a flange 12' that lies against the upper edge of the splash board, the splash board, this flange 12' and the vertical leg of the brace bar being secured together by a suitable bolt 17' that has preferably its head located so as to expose it only from the front of the structure.

Attention is also called to the fact that the vertical edge of the splash board is turned backward as shown at 24 and its extremity 25 turned inward, forming right angle flanges between which the brace bracket 6 is enclosed, thus concealing the said bracket. The inner flange 26 of the splash board 5 is doubled rearwardly and then forwardly as shown and rests against the wall 2 of the oven. Also the inner end 28 of the top shelf 12 is turned downward as at 29 and is secured to the oven wall 2 by means of suitable bolts (not shown) that pass through openings 30 formed therein.

For the purpose of firmly securing the lower rearwardly extending end 9 of the brace bracket, I provide a right angle supporting bracket that has a horizontal arm 31 fitting against the depending inside wall 32 of the rear end of the open burner frame 33 and the same is secured by bolts passing through two openings 34. The rearwardly extending end 35 of this supporting bracket receives on its top the end 9 of the brace rod which is secured by a suitable bolt passing through registering openings 36 made in the two parts. In this manner the lower end of the brace bar is firmly held in position.

Also the lower edge 37 of the splash board 5 is secured to the flange 32 of the open burner frame 33 by suitable bolts 38.

A back 39 for the top shelf 12 is located at the rear edge thereof and has its lower end turned rearward to form a flange 40 and its upper end correspondingly turned to form a flange 41. The inner edges of the flanges 40 and 41 are both turned downward as shown at 42 and 43, the latter forming a flange that rests against the back of the splash board 5. It will be noted that owing to this construction, the said shelf backing overlaps the rear edges of the shelf, thus making a finished appearance and not exposing the raw edges of the parts for accumulation of dirt or other foreign matter.

This construction as will be understood, produces a rigid support substantially invisible from the front, and the construction of the parts produces a splash board and its connecting members which are sanitary, and attractive in appearance.

The construction that is specifically described herein may be varied in some parts

without departing from the spirit and scope of the invention so long as such variation is within a fair interpretation of the appended claims.

Having thus described my invention, what I claim and desire to secure by Letters Patent is:—

1. In a range splash board construction, comprising a vertically arranged splash board, a brace rod attached to the rear side of the splash board and extending substantially throughout its height, the lower end of the rod having a horizontal laterally extending portion, and a frame to which the projecting end is secured. 80

2. A range splash board construction comprising a vertically arranged splash board, a vertical brace bar located at its outer vertical edge, said edge of the splash board doubled rearward to enclose the brace bar, thereby making a construction with no projections in front of the splash board and producing a sanitary construction. 85

3. A range splash board and a top shelf construction comprising a vertically arranged splash board and a horizontally inwardly extending top shelf, a brace bar L-shaped in construction with the vertical leg located back of the splash board and its horizontal leg located under the said top shelf, and means for securing the parts together whereby a substantially invisible support is provided for the splash board and the top shelf. 90

4. A range splash board and top shelf construction comprising a vertically arranged splash board, a horizontal inwardly extending shelf at the upper portion of the splash board, an L-shaped brace lever having its vertical portion located in rear of the splash board and its horizontal end located under the said shelf, the edge of the splash board turned around the said vertical portion of the brace rod for the purpose described. 105

5. A splash board and top shelf construction for ranges comprising a vertical splash board, an inwardly extending horizontal shelf located substantially at the upper portion of the splash board, an L-shaped brace rod having its vertical portion located at the back of the splash board and its horizontal portion resting under the said shelf, the edges of the said shelf turned downward for concealing the horizontal end, and means for securing the parts together. 115

6. A splash board and top shelf construction for ranges comprising a vertically arranged splash board, an inwardly extending shelf portion, an L-shaped brace rod having its vertical portion located back of the splash board and its horizontal portion under the said shelf, the lower end of the brace rod projecting rearward, and an open burner frame having projecting bracket to 120 125 130

which the rear extending end of the brace rod is secured for making a rigid support therefor.

7. A range splash board and top shelf construction comprising a vertically arranged splash board, an inwardly extending top shelf, an L-shaped brace rod having its vertical portion located back of the splash board and its horizontal end projecting under the said shelf, the said shelf having its edge depending to enclose the said horizontal end and the outer vertical edge of the splash board bent rearwardly around the said vertical portion of the brace rod, and means for securing the parts together.

8. A range splash board and top shelf construction comprising a vertically arranged splash board, an inwardly extending top shelf, an L-shaped brace bar having its vertical portion located back of the splash board and its horizontal portion located under the said shelf, the said shelf having its front and rear edges turned downward a depth substantially equal to the depth of the horizontal portion of the bar for concealing it, and means securing the parts together.

9. A range splash board and top shelf construction comprising a vertically arranged splash board, an inwardly extending top shelf, an L-shaped brace bar substantially L-shaped in cross section, the vertical portion of the bar located back of the splash board and its horizontal portion located under the splash board, the outer edge of the top shelf doubled downward and inward to engage under the horizontal portion of the brace bar, and means securing the parts together.

10. A range splash board and top shelf construction comprising a vertically arranged splash board, an inwardly extending top shelf, an L-shaped brace bar having the vertical portion located back of the outer edge of the splash board, the splash board doubled around the said brace bar, the brace bar being substantially L-shaped in cross section, the edges of the top shelf turned downward a depth substantially equal to that of the horizontal part of the brace bar, and a sheet metal triangular bracket under the horizontal portion of the brace bar, and means for securing the parts together.

11. A range splash board and top shelf construction comprising a vertically arranged splash board, an inwardly extending top shelf, an L-shaped brace bar located with its vertical portion at the back of the outer edge of the splash board, the top shelf resting on the horizontal portion of the brace

bar and shaped to conceal it, the lower end 60 of the brace rod extending laterally and connected with the open burner frame for the purpose described.

12. A range splash board and top shelf construction comprising an open burner 65 frame, a vertically arranged splash board, an inwardly extending top shelf, an L-shaped brace rod having its vertical portion located in rear of the splash board and its horizontal portion located under the shelf, 70 the lower end of the brace bar extending rearwardly and a rearwardly extending bracket connected with the open burner frame and with the rear extending end of the brace rod and means for securing the 75 other parts together.

13. A range splash board and top shelf construction comprising an open burner frame, a vertically arranged splash board, an inwardly extending top shelf, an L- 80 shaped brace rod having its vertical portion located at the back of the splash board and its horizontal portion located under the top shelf, means for securing the parts together, and a vertically arranged backing located 85 at the outer portion of the said top shelf, the said vertically arranged backing overlapping the rear edge of the top shelf and having its top and lower edges turned downwardly, and means for securing the lower 90 edge and the splash board together.

14. In a range splash board construction comprising a frame, a vertical splash board arranged at the rear edge thereof, a brace rod attached to the rear side of the splash 95 board and having its lower end horizontally rearwardly projecting, and the horizontal end connected with the said frame.

15. A splash board construction comprising a frame, a splash board extending vertically from the lower part of the said frame, a brace rod secured at the rear side of the splash board and its upper end extending forward over the said splash board, and a top shelf secured to the forwardly projecting portion of the brace rod.

16. A range splash board construction comprising a frame, a splash board extending vertically from its rear side, an L-shaped brace rod having its vertical portion located 110 at the rear of the splash board, and its lower end connected with the said frame, the upper end projecting forwardly and the top shelf secured to the projecting part of the rod.

In testimony whereof I hereunto affix my signature.

MINARD A. POSSONS.
